UNITED STATES PATENT OFFICE.

JOHN AUREDENN, OF CINCINNATI, OHIO.

KNITTING-MACHINE.

SPECIFICATION forming part of Letters Patent No. 355,047, dated December 28, 1886.

Application filed September 18, 1886. Serial No. 213,945. (No model.)

To all whom it may concern:

Be it known that I, JOHN AUREDENN, of Cincinnati, county of Hamilton, and State of Ohio, have invented certain new and useful

5 Improvements in Knitting-Machines, of which the following is a specification.

My invention relates to that class of knitting-machines having a cylinder carrying the needles surrounded by an outer rotating cylinder, which latter is provided with cams for raising and lowering the needles to make the stitch. The outer or rotating cylinder is usually provided with two sets of cams—one set for use when the cylinder is rotated to the right and the other set when the cylinder is rotated to the left. Each needle is provided with a projection, which rests on cams of the rotating cylinder. When the cylinder is rotated rapidly, it sometimes happens that a needle 10 fails to follow the proper course and jumps into the wrong groove. It is the particular object of my invention to provide means for effectually preventing the needle from leaving its proper groove.

25 In the accompanying drawings, Figure 1 is a perspective view of that part of a rotating cylinder provided with my improvement, which is provided with the cams for raising and lowering the needles. Fig. 2 is a top view 30 of my improvement in position on a rotating cylinder, the top cam, F, being omitted. Figs. 3, 4, and 5 illustrate modifications of my device, the top cam, F, being omitted. Fig. 6 is a side elevation of one of the needles in use in 35 the machine.

The rotating cylinder A is provided with a ledge, B, which extends entirely around the inside of the cylinder, except where the cams for raising and lowering the needles are placed. 40 A projection, n, from each of the needles N, one of which is shown in Fig. 6, rests on the top of the ledge B. The piece D is attached to the cylinder A between the ends of the piece B. It has two rather deep notches, d d', cut 45 in it. These notches are similar to each other in shape. Between the notches d d' is a horizontal face, d'', located at about the same level as the top of the ledge B.

Two cams, E E', somewhat triangular in 50 shape, are pivoted to the cylinder A at the points e and e', and hang down into the notches d d' in such position that their points e' rest on

the edge of the piece D on a level with the top of the ledge B. A double curved piece, F, is attached to the cylinder A immediately over 55 the center of the piece D. A guide-pawl, G, is preferably secured to the cylinder A in the position shown in Fig. 1.

With the machine in operation, the cylinder A generally rotates in the direction of the arrow. The different needles pass through the same various movements in succession. A needle which has its projection n resting on the ledge B is raised when the cam E reaches it, and the projection n passes through the groove 65 H between the top face of the cam E and the bottom of the piece F, and drops to the face d' on the piece D. Thence its course is through the groove I between the notch d' and the lower face of the cam E', the end e' of which is raised 70 by the projection n as the latter passes onto the top of the ledge B. When the machine is reversed, the projection n passes through the groove L between the piece F and the cam E', and through the groove M between the cam E 75 and the piece D.

It sometimes happens that when the projection n has passed through the groove H and dropped onto the face d' it bounces up into the groove L, instead of passing into the groove I; and, similarly, after leaving the groove L, when the machine is reversed, it occasionally passes into the groove H instead of the groove M. In either case the needle is usually broken. To avoid this accident I provide pawls to close the inner end of each of the grooves H and L. At the ends of each of the grooves H and L, I pass a wire, P, through the rotating cylinder A, the opening being large enough to allow the wire to rotate within it 80 freely. The inner end of the wire P is bent to form the pawl P'. The free end of the pawl is held against the lower face of the piece F, preferably by the means shown in Fig. 4. The outer end of the wire P is supported in the 85 bracket A'. The wire is surrounded by a spiral spring, O, one end of which is attached to the wire and the other is secured to the bracket or the cylinder. The action of this spring is to keep the free end of the pawl against the face 90 of the piece F.

In Figs. 2, 3, and 5 modifications of this device are illustrated. In Fig. 2 a boss, A², is shown, through which the wire P passes. The

wire is also provided with a long arm, P^2 , bent in the opposite direction from the pawl P' , and whose weight serves to keep the pawl P' in position. In the device shown in Fig. 3 the boss 5 A^2 is surrounded by a spiral spring, O , one end of which is attached to the boss or to the cylinder A , and the other end to the arm P^2 . This spiral spring keeps the pawl P' against the face of the piece F . In the device shown 10 in Fig. 5 a single spring, O , attached to a lug projecting from the cylinder A , serves to hold both springs in position.

The operation of the device as modified by my attachment is as follows: When the projection n from the needle meets the pawl P' in its passage through the groove H , the latter is readily pushed aside, allowing the needle to pass on, when the pawl is immediately brought back into position by the spring O or the arm 15 P^2 . The pawl P' over the opposite groove L , however, remains in place and prevents the projection n from slipping into this latter 20

groove, thus forcing it into its proper channel. Similarly, when the machine is reversed, the projection n is unable to pass, except through 25 the grooves L and M .

What I claim as new and of my invention, and desire to secure by Letters Patent, is—

1. In a knitting-machine, the combination of the cylinder A , ledge B , piece D , having 30 notches d d' , cams E E' , piece F , and wires P , having pawls P' , and means for holding the pawls P' across the grooves between the cams and the piece F , substantially as and for the purposes specified.

2. In a knitting-machine, the combination of the cylinder A , ledge B , piece D , having notches d d' , cams E E' , piece F , and wires P , having pawls P' , and springs O , substantially as and for the purposes set forth.

JOHN AUREDENN.
